UNITED STATES PATENT OFFICE

JEFFERY WALKER, OF BIRMINGHAM, ENGLAND

SHIP LOG

Application filed January 7, 1929, Serial No. 330,880, and in Great Britain November 8, 1928.

This invention relates to ship-logs and it refers more especially to those which are mounted on the taffrail and in an exposed position. It is also applicable to bridge logs.

5 Being relatively inaccessible, taffrail logs are frequently neglected and owing to absence of regular lubrication the mechanism wears out and becomes inaccurate, this wear often being accentuated by grit and water. 10 that enter the casing by way of the lubricating aperture which is left uncovered. To counteract possible omission to attend to the log regularly the casing is sometimes filled with oil, but this practice is disadvantageous 15 in that the oil finds its way to the front of the dial and fouls it.

This invention aims to overcome these objections and to provide a watertight log capable of running for lengthy periods in an 20 exposed position without attention and wherein the wear of the parts is not affected by the location of the log; a further object of the invention being to enable the reduction gearing to be readily removed and re- 25 placed in case of necessity.

Accordingly the invention provides a ship-log, primarily for fixing on the taffrail or other similarly exposed position, wherein the reduction gearing is housed independently of 30 the indicator movement and dial in disconnectable association within a casing which constitutes a watertight enclosure wherein the reduction gearing runs permanently in oil and the indicator movement and dial are located in a separate compartment to which 35 the oil has no access.

The mechanism is thus divided between an element containing the fast-running parts subjected to the most wear, and an element 40 containing the slowly-running or non-wearing parts, the two being adapted to be operatively united by assembly within said casing.

For example, part of said casing may accommodate a mounting supporting the primary spindle and its bearing and also supporting the first reduction gearing to which the primary spindle is coupled detachably 45 in the usual manner; while the other part of said casing, which may be formed integrally

with or be screwed to or otherwise arranged co-axially of the first part, may contain the indicator movement which may be so mounted that a partition fixed in said part of the casing prevents access of oil thereto, means being provided to effect an operative connection between said reduction gearing and the indicator movement. 55

For a taffrail log the aforesaid casing is adapted to be supported in the usual gimbal or other mounting whereby the log is secured upon the taffrail; while for a bridge log the casing, which is formed to fit into an aperture in the bridge structure, would terminate in a universal joint or otherwise suitably to enable the primary spindle to project at the requisite angle towards the rotator line. 60

Two constructional embodiments of the invention are illustrated, by way of example, 70 in the accompanying drawings, wherein:—

Figure 1 is a longitudinal section, and Figure 2 is a side elevation of a taffrail log the latter showing the reduction gearing withdrawn from the casing. 75

Figure 3 is a sectional elevation of a construction for a bridge log, the reduction gearing being shown withdrawn from the casing as in Figure 2. 80

Referring firstly to Figures 1 and 2, the log comprises a cylindrical casing 1 carried in the known manner by a gimbal pedestal 2 adapted to be secured suitably upon a ship's taffrail, which casing 1 is formed with an integral circular flange 3 of larger diameter than the casing to which flange a tubular housing 4 is secured by set screws 5, a bezel 6 being attached as usual to the flanged front end of the housing 4 to retain the usual glass front of the log. 85

7 and 8 are indicator pointers which move over appropriate scales marked on the face of a dial 9, the pointers being actuated by a suitable movement indicated comprehensively by the numeral 10 and carried by a circular baseplate 11 which is secured by screws 12 in an oiltight manner to the shoulder 13 formed integrally with the tubular casing 1. 90

The driving spindle for the indicator movement 10 terminates in a flattened spigot 14.

14 projecting axially rearwardly of the base-plate 11, and adapted to be connected operatively with the reduction gearing interposed between it and the primary spindle of the log.

5 15 is the aforesaid primary spindle which is provided with the usual eye 16 for the attachment thereto of the log line, and this spindle 15 is carried in anti-friction bearings 17, 17, arranged within the tubular extension or cage 18 of a cap or end piece 19 adapted to be screwed into the smaller end of the casing 1.

15 The reduction gearing, which is necessary to transform the speed of revolution of the primary spindle appropriately to the indicator movement, is indicated collectively by the numeral 20 and is borne by a circular and apertured plate 21 integrally with which is a screw-threaded boss 22 screwing into a ring 23 which is attached by screws 24 to a gland 25 screwing into the internally screw-threaded end of the tubular extension or cage 18; said gland 25 serving to adjust the anti-friction bearings 17, 17.

20 Engagement between the primary spindle 15 and the reduction gearing 20 is effected by a bifurcated end 26 on spindle 15 engaging a flattened spigot 27 on the first spindle of the reduction gearing 20. It will be seen that the reduction gearing 20 can therefore easily be disconnected when necessary, from the primary spindle 15.

25 The last spindle of the reduction gearing 20 is formed with a bifurcated end 28 which is adapted to engage the flattened spigot 14 projecting from the indicator movement.

30 By reference to Figure 2 it will be clear that the log mechanism is divided into two separable units, that is to say, the casings 1 and 4 containing the slow running indicator movement, and the cage 18 and cap 19 supporting the fast running reduction gearing 20; the latter therefore being withdrawable bodily from the chamber 29 constituted by the forward portion of the casing 1. This chamber 29 is adapted to be filled with lubricant wherein the reduction gearing runs and which is prevented by the base plate 11 from entering the housing 4 and fouling the indicator dial 9.

35 The bridge log illustrated in Figure 3 is mechanically similar to the log described with reference to Figures 1 and 2, and comprises a tubular body or casing 29 fitting slidably through a flanged collar 30 provided with screw holes 31 for its attachment to a suitable part of the bridge structure, and secured to said collar by a fly nut 30A, the casing 29 having secured to its front end by screws 32 the flanged back 33 of a casing 34 containing the indicator movement 10 and fitted with a bezel 35 and glass front to enclose the pointers 7 and 8 and the dial 9; the movement 10 being mounted, as before, on

a circular baseplate 11 attached by screws 12 in an oiltight manner to the back of the casing 34.

40 A flattened spigot 14 projects, as before, rearwardly through the circular baseplate 11.

45 The reduction gearing 20 is mounted on plate 21 and the last spindle of the gearing has the forwardly projecting bifurcated end 28, as before, for engagement with the spigot 14.

50 The plate 21 is carried by a circular member 36 connected to a universal joint 37 which is surrounded by a screw-threaded ring 38 adapted to screw on to the similarly threaded end 39 of the body or casing 29.

55 It will be seen that a completely watertight and grit-proof casing is provided for the log mechanism which is therefore subjected only to that wear which is due to normal use, and that by separating physically the two types of gearing and providing a detachable connection therebetween it is a matter of ease to remove bodily a worn reduction gearing and to substitute a new mounting and gearing without disturbing the indicating movement. Finally, notwithstanding that the first reduction gearing runs in oil, there is no possibility of leakage of oil through to and consequent fouling of the dial.

60 What I claim is:—

1. A ship log comprising an elongated open ended casing, a log indicator mechanism secured bodily to one end of the casing and having its driving spindle extended within the casing, a primary log spindle and reduction gearing operated thereby, means supporting said primary log spindle and reducing gearing and received bodily therewith within the casing through the other end of the latter, said gearing having means detachably engaging the extended portion of the driving spindle of the log indicating mechanism for operating the same.

65 2. A ship log comprising an elongated open ended casing, a log indicator mechanism secured bodily to one end of the casing and having its driving spindle extended within the casing, a primary log spindle and reduction gearing operated thereby, means adapted to be detachably secured to the other end of the casing and uniting said spindle and gearing together for bodily introduction into and withdrawal from the casing as a unit, and means operatively associated with said gearing and adapted to have detachable connection with the extended portion of the driving spindle of the log indicator mechanism for operating the same.

70 3. A ship log comprising an elongated open ended casing, a log indicator mechanism secured bodily to one end of the casing and having its driving spindle extended within the casing, a cap removably received upon the other end of the casing and nor-

mally closing the same, a primary log spindle and reduction gearing operated thereby, said primary log spindle and reduction gearing being carried bodily by said cap for introduction into and withdrawal from the casing as a unit, said gearing having means adapted to detachably engage the extended portion of the driving spindle of the log indicator mechanism for operating the same.

10 4. A ship log comprising an elongated open ended casing, a log indicator mechanism secured bodily to one end of the casing and having its driving spindle extended within the casing, a cap removably received upon 15 the other end of the casing, a primary spindle projecting through the cap and having bearing therein, reduction gearing carried by said cap, means having detachable connection with said primary log spindle and operatively 20 connected to said gearing for driving the latter, and other means actuated by said gearing and having detachable connection with the extended portion of the driving spindle of the log indicator mechanism for 25 operating the same.

5. A ship log comprising an elongated open ended casing, a plate detachably secured to one end of the casing and normally closing the same, a log indicator mechanism supported by said plate and having its driving spindle extended through the plate within the casing, a cap removably received upon the other end of the casing, a primary spindle projecting through the cap and having bearing therein, reduction gearing carried by said cap, means having detachable connection with said primary log spindle and operatively connected to said gearing for driving the latter, and other means actuated by said 30 gearing and having detachable connection with the extended portion of the driving spindle of the log indicator mechanism for 35 operating the same.

10 In testimony whereof he affixes his signature.

JEFFERY WALKER.
